UNITED STATES PATENT OFFICE

ANTHON AMBYE, OF ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS

ADJUSTABLE DRIVE FOR TOP AND BOTTOM DRAWING ROLLS OF SPINNING FRAMES

Application filed April 22, 1930. Serial No. 446,389.

This invention relates to spinning frames and particularly to the draft mechanism incorporated therein. The adjustment of the draft imposed upon the roving as it is spun constitutes one of the major factors in determining the character of the yarn produced by such machines. It follows, therefore, that adjustment must be made at frequent intervals. It is highly desirable, therefore, 10 that the means provided to accomplish this adjustment be readily accessible and at the same time positive and accurate in its function.

It is the general object of this invention to 15 provide such an adjustment having the desirable characteristics above suggested.

A specific object of the invention is to provide a mechanism which is situated at a convenient height and in a plane near the outer 20 limits of the space occupied by the machine.

The object of the invention is further to provide a draft mechanism in which a train of spur gears constitutes a connecting means between the feed and draft rolls.

25 A further object of the invention is to provide a draft mechanism in which the means for adjustment thereof is rendered accessible by extending the cross shaft associated with the feed rolls to a point adjacent the outer limits of the machine.

30 A further object of the invention is to provide a draft adjusting device which is simple and compact in design and which may be enclosed in a protecting casing of small dimensions.

35 Other objects and features will more fully appear from the following description in connection with the accompanying drawings and will be particularly pointed out in the 40 claims.

45 Only those elements with which the invention is directly concerned are illustrated since the remaining elements may be constructed in a manner well known to those skilled in the art.

In the drawings:

Fig. 1 is a partial transverse section through a spinning frame embodying the invention.

50 Fig. 2 is a side view of a portion of one

end of a spinning frame showing the draft mechanism and the speed changing device.

The invention is particularly adapted to spinning frames having two rows of spindles, each row having associated therewith a feed roll and a draft roll to produce the necessary draft, and wherein the feed rolls associated with each row are driven at the same speed by a transverse shaft while the draft rolls for each row are driven at the same speed by a separate transverse shaft. The speed ratio existing between the feed rolls and the draft rolls is determined by a train of gearing connecting the two transverse shafts. To vary the draft one of the gears of the train is made interchangeable with gears of different diameters.

It is one of the features of the invention to place the train of gearing in an accessible position so that the draft may be readily changed. To do this the transverse shafts above referred to are extended to a point adjacent the outer limits of the machine, at which point the train of gearing is attached. Since the transverse shafts are normally at a convenient height above the floor it follows that if the train of gearing is situated at the ends of their extensions it is readily accessible to permit an operator to change the draft.

As herein illustrated the mechanism for permitting adjustment of the draft is mounted within the casing 1 which is mounted on the end frame 2 of the machine. The rolls 3 and 4 which are commonly called the feed rolls function to supply roving to the mechanism from a suitable supply not shown. The feed rolls 3 and 4 extend throughout the length of the machine and are supported respectively in suitable bearings 5 and 6 secured to a bracket 7 mounted on the usual longitudinal supporting members 8 and 9 which are in turn supported from the end frames of the machine.

The feed rolls 3 and 4 are driven at equal speeds by means of a transverse shaft 10 rotatably supported in the bearings 11 and 12 on the bracket 7. The shaft 10 has thereon a bevel gear 13 which meshes with a gear 14 on the feed roll 3. Another gear 15 on the

shaft 10 meshes with a gear 16 on the feed roll 4. The two feed rolls are thus driven by the shaft 10 which is itself driven by a transverse shaft 17 through a train of gearing to be herein after more fully described.

The shaft 17 is mounted at one end in a suitable bearing in the bracket 18 which is mounted on the longitudinal support 19 and is supported at its other end in a suitable bearing 20 which is fixed to the longitudinal support 21. The supporting members 19 and 21 extend the full length of the machine and are secured to the end frames thereof. A bevel gear 22 is fixed to one end 15 of the shaft 17 and meshes with a bevel gear 23 on the draft roll 24 while at the other end of the shaft 17 is secured a bevel gear 25 which meshes with a bevel gear 26 on the draft roll 27. The bevel gears above described are so 20 proportioned that the two draft rolls rotate at the same speed.

As above suggested a train of gearing is provided between the two transverse shafts for determining the relative speed of the feed 25 rolls 3 and 4 and their cooperating draft rolls 24 and 27. Inasmuch as the shafts 10 and 17 are parallel the gear train is desirably composed of a series of spur gears which are of maximum efficiency in the transmission of 30 power. The shaft 10 is extended at one end to enter the casing 1 and is rotatably supported therein in a bearing 28 formed in a partition wall 29 within the casing. Upon the extended end of the shaft 10 is mounted 35 a driving gear 30 which is one element in the connecting train of gearing between the shaft 10 and the shaft 17. It will be noted that by extending the shaft 10 it is possible to locate the casing 1 which encloses the gears in an 40 accessible position near the outer limits of the space occupied by the machine.

Adjacent the end of the shaft 17 is fixed a gear 31 which meshes with a gear 32 rotatably mounted on a stud shaft 33 fixed in the partition 45 29 within the casing. The gear 32 serves to transmit the rotation of the shaft 17 to a shaft 34 through a gear 35 mounted on the shaft 34 and meshing with the gear 32. The shaft 34 is rotatably mounted in a bearing in 50 a lever 36 which is pivoted upon the stud shaft 33. The lever 36 may be moved therefore about its axis and at the same time maintain the gears 32 and 35 in mesh. Detachably mounted on the shaft 33 is a change gear 37 55 which meshes with the gear 20 on the shaft 10.

The lever 36 is extended to a point outside the casing 1 to form a handle 38 and has therein adjacent the handle a locking bolt 39 which extends through a slot 40 in the partition 29. 60 The slot 40 is concentric with the axis of the lever which permits movement thereof when the bolt has been loosened. By tightening the bolt in the slot the lever is held in fixed position to maintain the gear 37 in mesh with 65 the gear 20. A positive drive is thus estab-

lished between the shaft 17 and the shaft 10 progressively through the gears 31, 32, 35, 37 and 20.

If it is desired to change the draft a gear of the proper size must be substituted for the gear 37. No definite order in which to perform the various movements necessary to do this need be followed. A desirable method is to first loosen the bolt 39 to free the lever 36, then the gear 37 is removed and the new gear substituted therefor. The lever is then moved about its pivot until the new gear properly meshes with the gear 30 after which the bolt 39 is tightened to lock the gears in mesh. 70

The speed rolls and the draft rolls have herein been referred to as single rolls. It is to be understood, however, that the feed rolls have associated therewith the usual pressure rolls 41 while the draft rolls are provided with cooperating pressure rolls 42. A proper bite is thus established at the feed roll and at the draft rolls to draw the roving. 80

The mechanism may be driven in any suitable manner. A desirable method is to extend the draft roll 24 into the end frame 2 and secure thereon a gear 43 which may be directly connected to the jack shaft of the machine or any driven element thereof. 90

Having thus described the invention, what is claimed as new, and desired to be secured by Letters Patents, is:

1. In a spinning frame, a casing located near the outer limits of the machine in a position accessible to the operator, two longitudinally-extending feed rolls at opposite sides of the frame, a transverse shaft in driving engagement with both of said feed rolls and extending into said casing, a train of gearing within the casing, a gear on the end of said transverse shaft within the casing and in driving engagement with one end of said gear train, two longitudinally-extending draft rolls at opposite sides of the frame, a transverse shaft in driving engagement with both of said draft rolls, a gear on said last-named shaft in driving engagement with the other end of said gear train, an interchangeable element in said train whereby the speed ratio of the feed rolls and the draft rolls may be changed to produce the desired draft and means to drive the mechanism. 100

2. In a spinning frame, two longitudinally-extending feed rolls, two longitudinal draft rolls co-operating therewith to draw the roving as it is spun, a transverse shaft in driving engagement with both of said feed rolls, a second transverse shaft in driving engagement with said draft rolls, a driving gear on both of said transverse shafts, a train of gearing connecting said transverse shafts, a lever pivoted on the axis of one of the gears in the gear train, a pair of concentric gears mounted to rotate together upon said lever and constituting a part of said gear train, one 110

of the gears of said pair meshing with the gear in the pivotal axis of the lever and the other being interchangeable and positioned by movement of the lever into mesh with the driving gear on one of the said transverse shafts and means to lock the lever in position to maintain the gears in mesh.

3. In a spinning frame, two longitudinally-extending feed rolls, two longitudinally-extending draft rolls co-operating therewith to draw the roving as it is spun, a casing located near the outer limits of the machine in a position accessible to the operator, a transverse shaft in driving engagement with said feed rolls extending into said casing, a second transverse shaft in driving engagement with said draft rolls, a driving gear on each of said transverse shafts, a train of gearing within the casing connecting said transverse shafts, a lever pivoted within the casing on the axis of one of the gears in the gear train, a pair of concentric gears mounted to rotate together upon the lever and constituting a part of the gear train, one of said pair of gears being interchangeable and positioned by movement of the said lever into mesh with a driving gear on one of the transverse shafts, the other gear of the pair meshing at all times with the gear on the shaft about which the lever pivots and means to lock the lever in adjusted position.

In testimony whereof, I have signed my name to this specification.

ANTHON AMBYE.
